UNITED STATES PATENT OFFICE.

ERNST ENGSTFELD, OF PHILADELPHIA, PENNSYLVANIA, ASSIGNOR TO
AUGUSTUS A. LAZARUS, ISAAC A. SCHWARZ, AND BENJAMIN LIPPER,
ALL OF SAME PLACE.

DESIGN FOR A DRESS-TRIMMING.

SPECIFICATION forming part of Design No. 21,033, dated September 15, 1891.

Application filed August 3, 1891. Serial No. 401,583. Term of patent 3½ years.

To all whom it may concern:

Be it known that I, ERNST ENGSTFELD, a subject of the Emperor of Germany, and a resident of Philadelphia, Pennsylvania, have 5 invented a new and original Design for a Dress-Trimming, of which the following is a specification.

My design for a dress-trimming is fully shown in the accompanying drawing, which 10 represents a face view of a piece of the trimming.

The design comprises the central braid-like strip *a*, a cord *b*, following a sinuous course, so as to cross the face of the braid *a* and form 15 loops on opposite sides of the same alternately, and an edging composed of fan-like figures *d*, formed by cords carried back and forth throughout paths of varying length.

The braid strip *a* has an edging *f*, and the fan-like figures at the edges of the trimming are crossed by bands *g*; but these latter features are immaterial, the essential features of the design comprising the central braid-like strip, the sinuous cord, and the fan-like figures forming the edging. 20 25

I claim—

The design for a dress-trimming, substantially as described, and as shown in the accompanying drawing.

In testimony whereof I have signed my 30 name to this specification in the presence of two subscribing witnesses.

ERNST ENGSTFELD.
